UNITED STATES PATENT OFFICE.

STEPHEN M. ESTES, OF CLINTON, ASSIGNOR OF ONE-HALF TO CHESTER A. HODGE, OF BELOIT, WISCONSIN.

SPOKE-TENONING AND FELLY-BORING MACHINE.

SPECIFICATION forming part of Letters Patent No. 240,014, dated April 12, 1881.

Application filed January 26, 1881. (Model.)

To all whom it may concern:

Be it known that I, STEPHEN M. ESTES, of Clinton, in the county of Rock and State of Wisconsin, have invented a new and valuable 5 Improvement in Spoke-Tenoning and Felly-Boring Machines; and I do hereby declare that the following is a full, clear, and exact description of the construction and operation of the same, reference being had to the annexed drawings, making a part of this specification, and to the letters and figures of reference marked thereon.

Figure 1 of the drawings is a side view. Fig. 2 is an end view. Fig. 3 is a plan view. 15 This invention relates to devices for boring, tenoning spokes, &c.

The invention consists in the construction hereinafter described, and particularly pointed out in the claims.

20 In the drawings hereto annexed, A is a bench supported upon legs a, and having the longitudinal slot B near one end.

C is a post, whose tenon b projects down through slot B and is held by the nut c. Through 25 tenon b is a slot or screw-threaded hole, through which passes the screw-rod D, having handle d, by means of which post C can be moved along the bench A. Post C is slotted transversely at e', forming arms E E'. Journaled in this slot e' 30 are the gear-wheels F G H, the shaft f of the first having the cranked handle f' for operation.

Passing through holes g g in arms E E and hub h of wheel H is a shaft, I, carrying a chuck, K, with set-screw k at one end and a balance-wheel, L, at the other end, toward cranked handle f'. A slot or groove, i, on shaft I engages a pin, h', on the inside of hub h, so that said shaft will turn with the wheel H, but can be slid lengthwise independent of the wheel.

40 Extending to one side from the base of post C is an arm, M, having at its end an upright post, N, extending above at n and below at n'.

Attached to arm M, near to bench A, is another post, P; having at or near its bottom the 45 pair of slots p p'. Passing through these slots are treadles Q Q', pivoted to the lower end of post N, and connected by rods q q' with the arms r r' of the triple lever R, which is pivoted to the upper part of post P. The third arm, r³, 50 of this lever is connected to a rigid rod, S, made

fast to a lever, T, which is pivoted to the upper end of post N, and whose other and forked end, t, straddles a groove, v, in shaft I.

Lengthwise of bench A, upon the end away from slot B, and upon the side of post C to 55 which the chuck end of shaft I projects, is a table, U, hung to said bench by transverse swinging staples or loops u u, having their ends u' u' extending into holes in the sides of the bench and their bodies u² u² passed through 60 loops s' s', by which they are held in grooves t' t' at the ends of said table. This table has on top the longitudinal grooves r² r².

Projecting through a central enlarged slot in the table U is a rod, V, made fast to bench 65 A, and having a nut, a², at its top.

W is a platform, having ribs w w on its under side, lengthwise, and a hole, w', near its center. This platform is placed on table U, the ribs w w resting in grooves r² r² and the rod V 70 passing through hole w'.

X is a lifting-screw, having the handle x, and projects through a hole, b², in the bottom of bench A, and comes up under table U.

Made fast to the side of post P away from 75 post C is a slotted gage, Y, held tight by a binding-screw, Z, passing through slot y into post P.

This device can be used for boring, drilling, or cutting of any kind by putting the shank of the implement into chuck K and making it fast 80 by screw k.

For tenoning spokes the hub, with the spokes inserted, is placed on platform W, with rod V passing through the bore, and held tight by nut a².

85 By the lifting-screw X the table U is lifted up and the platform W rises, the ribs w w sliding in grooves r² r², and rod V keeping the said platform from horizontal motion until the work is at the proper height for the tool.

A shaft carrying a chuck and supported in bearings in such a manner that the same may be advanced and retracted by a hand-lever is not new, and such a construction is not claimed herein.

90 A tenoning-tool is made fast in the chuck K, and the gage Y is set to allow the swinging lever T, and consequently the shaft I, the proper play for the determined length of stroke. The post C, with its various devices, is set up to the 95 100

work by the rod D. Power is applied to the crank f' of shaft f, and through the gear-wheels is transmitted to shaft I, which causes the tool to turn. As it cuts, the shaft is forced inward by pressing on the treadle Q, which pulls lever T and shaft I toward the work. After finishing the tool is withdrawn by pressing on the other treadle, Q'.

Other classes of work can be placed on the platform W and held in any proper manner to be operated on.

In operating on spokes it may be advisable to place a support under them on top of platform W.

15 Z' is a T-gage designed to guide the spoke while driving to the required dish of wheel.

What I claim is—

1. Shaft f, having crank f' , wheels F G H, the latter having a pin, h', on the inside, in combination with shaft I, having grooves i and v , forked lever T, and treadles for operating the same, substantially as described.

2. In a tenoning and boring machine, the combination of the adjustable post C, carrying 25 the arm M, having slotted post P and post N,

the pivoted treadles Q Q', rods qq' , triple lever R, and pivoted forked lever T, with the grooved shaft I i and gearing F G H, substantially as and for the purposes set forth.

3. In a tenoning and boring machine, the 30 combination, with the bench A, of the swinging table U, having central opening and grooves, $r^2 r^2$, connected by loops $u u$ to the bench A, with the platform W, having ribs $w w$ on its under side, lengthwise, and a hole, w' , near its 35 center, and the rod V and lifting-screw X, substantially as and for the purposes set forth.

4. Table U, held to bench A by swinging loops, and provided with grooves on top, in combination with platform W, having ribs w 40 w on its under side, and a lifting-screw, substantially as described.

In testimony that I claim the above I have hereunto subscribed my name in the presence of two witnesses.

STEPHEN M. ESTES.
